UNITED STATES PATENT OFFICE.

GEORGE A. LOWDELL, OF SAN DIEGO, CALIFORNIA.

PEN-NIB.

1,307,203.

Specification of Letters Patent. Patented June 17, 1919.

Application filed August 9, 1916. Serial No. 113,997.

To all whom it may concern:

Be it known that I, GEORGE A. LOWDELL, a citizen of the United States, residing at San Diego, in the county of San Diego and 5 State of California, have invented certain new and useful Improvements in Pen-Nibs; and I do hereby declare the following to be a full, clear, and exact description of the invention, such as will enable others skilled 10 in the art to which it appertains to make and use the same.

This invention relates to writing pen nibs, and its primary object is to admit of the nib being conveniently removed from a pen 15 holder without necessitating the engagement of the nib by the hand of the operator, thereby preventing the hand being soiled by ink which adheres to the nib.

Another object of the invention is the provision of a nib that will admit of the above 20 object being carried out, and which can be as cheaply manufactured as a nib of ordinary construction.

Other objects will appear and be better 25 understood from that embodiment of my invention of which the following is a specification, reference being had to the accompanying drawing forming a part thereof, in which:

30 Figure 1 is a top plan view of the pen nib, showing the same removed from a holder.

Fig. 2 is a longitudinal sectional view, taken through Fig. 1.

Referring to the drawing in detail, the 35 numeral 1 designates a pen holder of ordinary construction, and the numeral 2 designates, as an entirety, a pen nib of the improved construction. The nib shown in the drawing resembles a nib of ordinary construction, but is provided at a point intermediate the writing point and the shank of the nib with a shoulder 3. This shoulder 3 is of crescent shape, as shown in Fig. 1. The nib 2 and shoulder 3 are preferably 40 formed by a single stamping, and the metal forming the shoulder 3 is preferably forced

outwardly, as shown in the drawing, but if desired the metal can be forced inwardly, so as to admit of the upper edge of the shoulder lying flush with the outer surface of the 50 nib, or in other words a recess can be formed in the upper side of the pen nib and having one wall of the recess providing a shoulder.

When a nib, constructed in the manner of the foregoing, is associated with a pen holder, 55 and it is desired to remove the same without necessitating the engagement of the nib by the operator's hand, the end of the shank of another nib is positioned to and engaged behind the shoulder 3 on the nib 2 and which 60 is associated with the pen holder, and outward pressure exerted on the shoulder so as to effect withdrawal of the nib from the pen holder. It will, of course, be understood that if desired the shoulder can be engaged 65 by the tip of one of the operator's fingers, or thumbs so as to admit of the removal of the nib from the holder in this manner.

It is evident that various changes might be resorted to in the construction, form and 70 arrangement of the shoulder without departing from the spirit and scope of the invention: Hence I do not wish to limit myself strictly to the structure herein described and claimed.

Having thus described my invention what 75 I claim as new, is:

As an article of manufacture, a writing pen nib having a curved shoulder of substantially U-shaped form in cross section 80 pressed outwardly from its body without severing the body to provide an abutment for receiving the withdrawal force so as to permit of the withdrawal of the pen nib from a pen holder without danger of the collapsing 85 of the shoulder.

In testimony whereof I affix my signature in presence of two witnesses.

GEORGE A. LOWDELL.

Witnesses:

JOHN C. CHRYSTAL,
BENJAMIN H. PHILLIPS.
